(57) **CLAIM**

The ornamental design for an orienting and driving system for roofing nails, as shown and described.

DESCRIPTION

FIG. 1 is an isometric illustration of the nail orienting device of the design;

FIG. 2 is a front elevational view of the nail orienting device of the design, the rear elevational view being a mirror image of the front elevational view;

FIG. 3 is a side elevational view of the nail orienting device of the design, the opposite side elevational view being a mirror image thereof;

FIG. 4 is a plan view of the design;

FIG. 5 is a bottom view of the design;

FIG. 6 is a side elevational view of the nail retrieving and driving implement of the design, the opposite side elevational view being a mirror image thereof;

FIG. 7 is a front elevational view of the nail retrieving and driving implement of the design;

FIG. 8 is a rear elevational view of the nail retrieving and driving implement of the design;

FIG. 9 is a top view of the nail retrieving and driving implement of the design;

FIG. 10 is a bottom view of the nail retrieving and driving implement of the design; and,

FIG. 11 is an elevational view showing the nail retrieving and driving implement and a portion of the nail positioning and orienting device of the design and further showing a nail having been retrieved from the nail positioning and orienting device of the design by the nail retrieving and driving implement of the design.

The elements are shown separately in FIGS. 1-10 for ease of illustration and the broken lines shown in FIG. 11 are for illustrative purposes only and form no part of the claimed design.
